ABRADING APPLIANCE

Kenneth H. Bowen, Auburn, N. Y., assignor to
 Columbian Rope Company, Auburn, N. Y., a
 corporation of New York

Application May 14, 1938, Serial No. 208,071

6 Claims. (Cl. 51—195)

This invention relates to improvements in abrading appliances such as discs or wheels to which an abrasive material is applied and, particularly, to a disc adapted to carry an abrasive material on its side surface, as distinguished from its peripheral surface.

One object of the invention is to provide a circular body adapted to function as an abrading member, in the sense that it is coated with an abrasive material, which member can be produced economically without detracting from its efficiency under operating conditions.

Another object is to provide a member of this type formed of promiscuously associated fibres secured together in the form of a web with means incorporated in the web to facilitate handling thereof in the production of the member, in that there is little, if any, likelihood of the web breaking or rupturing while being manipulated.

A still further object of the invention is to provide an abrading member of disc-like formation adapted to be flexed laterally in the use thereof, the abrasive being on the side face of the disc, and which member will be of better wear-resisting properties so far as concerns resistance to disintegration of the member by the strains imposed thereon by this lateral flexing action.

More specifically, the invention contemplates an abrading member composed of a plurality of laminations of fibres, preferably vegetable fibres, with each lamination comprising a reinforcing member, preferably in the form of a fabric sheet embedded in the lamination with the fibres disposed on opposite sides of the fabric and with portions or groups of the fibres projecting through the reinforcing fabric, this being the sole means of attachment of the fibres to the fabric during a portion of the formation of the member, or until the material is treated with a binder by which the several laminations are secured together in a unitary mass.

With these and other objects in view, the invention consists in certain details of construction and combinations and arrangements of parts, all as will hereinafter be more fully described, and the novel features thereof particularly pointed out in the appended claims.

In the accompanying drawing—

Figure 1 is a perspective view of an abrading member commonly known in the industry as a pad;

Fig. 2 is a perspective view of a section of the web material of which the abrading member is composed; and

Fig. 3 is a diagrammatical illustration of the apparatus used in forming the web of fibres.

Pads of the type adapted for the purposes of illustrating the present invention are adapted to have an abrasive material 10 dusted or otherwise applied to their side faces, this operation being known as the "heading-up" of the pad. In use, the coated face of the pad is pressed against the work and the pad must possess a certain degree of resiliency or flexibility so that it will be capable of flexing laterally when pressed against the work. This flexing action, of course, imposes rather heavy and continuous strains on the pad and is the determining factor, so far as concerns the life or length of usefulness of the pad, as the abrasive coating can always be renewed. In view of this, the present pad is made up of a plurality of laminations of fibres 11, and each lamination has incorporated therein a reinforcing member 12 which aids in preventing disintegration of the respective laminations by reason of the fact that it tends to prevent separation of the fibres of the lamination.

In the preferred embodiment of the invention, this reinforcing element is in the form of a sheet 25 of fabric with the fibres 11 arranged on opposite sides thereof, and each lamination is formed of a circular blank of material of this nature cut from a web of such material. As illustrated in Fig. 2, the web may be of continuous formation 30 and, to facilitate handling of the web in the manufacture of the finished product, the fibres 11 are attached to the reinforcing fabric by having certain of the fibres projecting through the fabric. As illustrated more or less diagrammatically in Fig. 3, the reinforcing fabric, with fibres 35 on opposite faces thereof, is passed through what is known in the industry as a "needling" machine, this machine comprising barbed needles 13 adapted to be pushed or projected through the web 40 formed by the fabric and fibres, the barbs causing small groups of the fibres to be pushed or drawn through the fabric from one side to the other, so as to interlock the fibres with the fabric. This is more clearly illustrated in Fig. 2 where 45 the fibres are shown as having been pulled off one side of the fabric to expose fibres projected through from the other side of the fabric, as indicated at 14. Thus, the layer of fibres on each side of the fabric becomes attached to the fabric 50 and, in addition, these tufts of fibres that are engaged by the needles in this so-called needling operation tend to interlock the fibres of each layer, so that there is little, if any, likelihood of the web rupturing or breaking or disintegrating 55

during the handling thereof. As will be understood, circular blanks or discs are cut from this web in the production of the present abrading member and a number of these discs or blanks 5 laid one upon another to form a pad of the desired thickness, the number of blanks used in a given pad depending, of course, upon the thickness of the pad desired and the thickness of the individual blanks. The discs or blanks are im- 10 pregnated or treated with a suitable binder, for instance, latex cement, either before or after being laminated and, after being laminated in pad form, they are placed under heat and pressure for curing and to reduce them to the de- 15 sired density.

It has been found that the use of this reinforcing member in the pad, or rather in the laminations constituting the pad, allows considerable flexing of the pad in use, without undue 20 permanent deformation or excess fatigue or wear on the pad. In addition, particularly where a canvas reinforcing member is used in the laminations, the same constitutes strengthening means against centrifugal forces which are set up in 25 the use of the wheel, it being remembered that the wheel is rotated at considerable speed in the abrading operation. Also, the presence of the reinforcing fabric, with the fibres extending therethrough from opposite sides thereof, also 30 aids in resisting centrifugal action, supplementing the binding action of the binder used in uniting the several laminations and fibres constituting the same. Again, this tying together of the fibres themselves and the fibres to the reinforcing 35 fabric by the so-called needling operation, tends to securely interlock them. This feature is not only of importance so far as the life of the finished pad is concerned, but it also greatly facilitates handling of the web of fibres in the production of the blanks and the handling of the blanks in laminating them to form the pad. This is especially true where all these steps are 40 performed before application of the binder to the fibres.

It will be appreciated that, while a pad only is 45 illustrated in connection with the disclosure of the present invention, the same is not limited to this specific use, as it lends to the production of abrading wheels of increased strength and wearing properties. Neither is the invention limited 50 to the use of any particular type of fibre, although

a vegetable fibre and a fabric reinforcing material is preferred.

What I claim is:

1. A circular disc-like body for an abrading member composed of a plurality of laminations 5 of fibres, each lamination having a reinforcing member therein with portions of the fibres of the lamination projecting through said reinforcing member, and a binder securing said laminations in a unitary mass.

2. A disc-like body for an abrading member composed of a plurality of laminations of fibres, each lamination having a fabric reinforcing member extending therethrough with the fibres of the lamination projecting through said fabric, 15 and a binder uniting said laminations in a unitary mass.

3. A disc-like body for an abrading member comprising a lamination consisting essentially of a sheet of reinforcing material and a layer of 20 promiscuously disposed fibres covering the side surface of said sheet with portions of the fibres projecting through said sheet, and a binder uniting said fibres and reinforcing sheet in a unitary mass.

4. A disc-like body for an abrading member adapted to flex laterally, said body being composed of a plurality of laminations, each lamination consisting essentially of a sheet of reinforcing fabric and a layer of fibres covering the side 30 surface of the fabric with groups of the fibres projecting through the reinforce fabric, and a binder uniting the several laminations in a unitary mass.

5. A disc-like body for an abrading member 35 adapted to flex laterally, said body comprising a lamination composed of vegetable fibres with a sheet of reinforcing material embedded therein, the fibres being attached to said sheet by projecting therethrough from opposite sides 40 thereof, and a binder uniting said laminations in a unitary mass.

6. A disc-like body for an abrading member adapted to flex laterally, said body comprising a lamination formed of a fabric sheet with a layer of fibres on each side thereof, groups of the fibres of each layer being disposed transversely of the layer and projecting through said fabric sheet, and a binder uniting said fibres and fabric in a unitary mass.

KENNETH H. BOWEN.
